(57) **CLAIM**

The ornamental design for a golf club head, as shown and described.

DESCRIPTION

FIG. 1 is a rear, toe-side, bottom perspective view of the golf club head;

FIG. 2 is a rear, heel-side, bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a toe-side elevational view thereof; and,

FIG. 8 is a heel-side elevational view thereof.

The broken lines depict portions of the golf club head that form no part of the claimed design. The dot-dash chain lines depict boundaries of the claimed design, and thus form no part of the claimed design. The three areas having respectively different density stippling depict areas that each has a contrasting appearance from the other of the areas having respectively different density stippling.
